Inventor,
A. MacGregor

UNITED STATES PATENT OFFICE

2,233,366

ROUGE OR PAINT REFILL CONTAINER

Agnes MacGregor, Seattle, Wash.

Application March 13, 1940, Serial No. 323,775

2 Claims. (Cl. 132—79)

My invention relates to improvements in rouge or paint containers, which to my knowledge is new, forming a construction which makes it possible to incorporate any number of specially made 5 pockets, or berths, arranged preferably around a complete circle, equidistant from a common axis, and adapted to receive rouge or paint receptacles of arched concavity or any form that will serve the use. The said receptacles being 10 locked within the said berths by special means of invention, which when empty are removed by means involving invention and refilled by the same inventive act reversed. A further object of this creation is to provide an inventive convenience thru adoption of this plurality of rouge or paint receptacles filled with various colors of rouge and eye shadow or paints, enabling the user 15 to blend colors to match dress apparel designs or for other purposes. Means being provided for simultaneous covering of the plurality of receptacles holding the rouge or paint.

I attain these objects by manufacture illustrated by the accompanying drawing, in which:

Figure 1 is a top plan view of the manufacture; 25 Figure 2 is a bottom plan of same with the bottom disc cut away to show the central disc; Figure 3 is a vertical and complete section showing the working manufacture; Figure 4 is a section of the characteristic, arched, concave rouge or paint 30 receptacle adapted for insertion into the manufacture's berth; Figure 5 is a plan view of the receptacle.

Like reference numerals refer to like parts thruout the several views.

35 Discs 3, 4 and 5 are independent parts movable about the common axis 1, and which axis consists of a metallic screw which is unthreaded over a distance equal to the thickness of disc 3 and is threaded the remainder of its length occupied by the thickness of discs 4 and 5. Discs 4 and 5 are threaded in order to receive threads 2 on screw 1.

A key slot 15 is made an essential part of disc 4 so that when any key 16 is passed thru a hole, 45 previously drilled thru screw 1, it serves to lock 4 against 3 when 4 has been screwed up against 3 to the required tension for rotation of said disc 3, a detail which will follow under operative specifications. Following the proper placing of disc 4, 50 adjacent to disc 3, comes the placing of disc 5 by screwing it upon the screw 2 thread until it reaches a position against disc 4 that is normally tight, but at a position where 10 aligns itself at a position midway between any two holes 9. When 55 this position is ascertained lock screw 18 is screwed

into recess 17, spotted upon disc 4. It is to be noted that screw 1 is provided with a screwdrive recess at its bottom (Fig. 2) and is for the purpose of backing out the said screw, after removing key 16, in case that the unit must be taken apart 5 for any reason.

The concave, arc shaped, receptacle 12 fits into counterbored holes 9 and against shoulders 13. The counterbored shoulders 13 serve to prevent the receptacle 12 from passing out thru the top, 10 and as a result are held permanently in place by the bottom disc 5 when the hole 10 takes a position between any two holes 9. The receptacle 12 is designed to hold its contents of rouge or paint within the arched concavity 14 and has acquired 15 this shape by reason of necessity and is due to the convenience it affords in the removal of the contents either by a finger or a brush. It is also clear that there are no corners for making difficult the removal of all of its contents and constitutes invention. In order that the contents of a plurality of rouge or paint receptacles 12 may be protected against physical damage in any way, the top disc 3 is moved in any direction to a position where the tongues 19 overlap all of the holes 25 9 simultaneously. Reference 7 denotes a passage way cut into hole 8 to make provision for free movement of a finger or brush in removing the contents of 12.

In the manufacture and operation of my rouge 30 and paint refill container I proceed to screw disc 4 upon 1 until it contacts disc 3 and provides a condition or tension that requires some force to turn said disc 3 about its axis 1. A hole is then drilled in 1 in alignment with slot 15 and key 16 35 is inserted. This moves disc 4 against disc 3 and makes it possible to move disc 3 about the axis 1 without either tightening or loosening disc 4 upon thread 2. Following this I screw disc 5 upon thread 2 until it will reach disc 4 and be 40 fairly tight when loading hole 10 is spotted between any two holes 9 and is then followed by tightening set screw 18 against 4 at recess 17. When I load or fill all of the berths 9 with receptacles 12 and its contents, I unloosen set 45 screw 18 and turn disc 5, usually to the left, as a right hand thread is recommended, and when it reaches the first berth 9 a receptacle is dropped in, and so on to the second berth 9 etc., until the bottom 5 has passed thru the arc of a complete circle, 50 when all of the berths 9 are filled. Having thus been filled disc 5 is turned back again to the right until it reaches its original locked position in recess 17 upon disc 4. The plurality of rouge or paint receptacles are now locked within their 55

berths and the top disc 3 is turned so that tongues 19 overlap and simultaneously cover all of the receptacles within 9. It will be understood that the bottom disc 5 is provided with but one filling hole 10 thru which all receptacles must pass in order to fill all of the berths 9 with receptacles 12. At 11 is a slot cut in disc 5 for the sake of convenience of placing and removing any receptacle 12 thru common hole 10.

10. I claim:

1. In a refillable rouge or paint container, the combination of a common concave, or other, rouge or paint receptacle, and a plurality of holding berths designed to hold said receptacles and arranged around an equidistant common axis, with provision for discharging and refilling said berths through a common bottom hole with the said rouge or paint receptacles, said common

bottom hole being movable about a common axis so as to permit alignment of holding berths and the common bottom hole and for overlapping same to prevent bottom escape of said rouge or paint receptacles, and means for locking same 5 with a set screw, substantially as described.

2. A refillable rouge or paint container, the combination of a concave rouge or paint receptacle, held within a plurality of berths with counterbored shoulders to prevent escape at the top, 10 arranged equidistant from a common axis, provided with a cover having corresponding holes specially slotted out on their outer side providing free access to the rouge or paint and means for rotating said cover about a common axis for 15 simultaneous opening and closing of said rouge or paint receptacles, in the manner described.

AGNES MACGREGOR.
